UNITED STATES PATENT OFFICE.

CLARENCE JANES, OF ONEIDA, NEW YORK.

PROJECTILE.

1,305,216.

Specification of Letters Patent. Patented May 27, 1919.

Application filed December 11, 1917. Serial No. 206,634.

To all whom it may concern:

Be it known that I, CLARENCE JANES, a citizen of the United States, residing at Oneida, in the county of Madison and State of New York, have invented new and useful Improvements in Projectiles, of which the following is a specification.

This invention relates to projectiles of the type designed to be charged with high explosives, and the object is to provide means for preventing the premature firing of the charge.

A further object is to provide a magazine adapted to maintain a stationary position, 15 so far as rotary movement is concerned, during the flight of the projectile, whereby the shock incident to the sudden rotation of the body portion of the shell, imparted by the rifling of the gun, shall be avoided, and 20 the charge maintained intact until set off by the operation of the firing mechanism.

A still further object is to provide in a shell having a body portion comprising an outer casing, a separate nose portion and a 25 separate breech portion, means for mounting a magazine independently of all of said elements, said breech portion and nose portion being connected by a longitudinal member coincident with the main axis of the 30 shell and permitting rotation independently of the magazine.

In the accompanying drawings:

Figure 1 is a view in elevation with parts shown in dotted lines.

Fig. 2 is a view in longitudinal section.

Fig. 3 is a rear end view.

Fig. 4 is a section on the line 4—4 of Fig. 2.

Fig. 5 is a section on the line 5—5 of 40 Fig. 2.

Fig. 6 is a section on line 6—6 of Fig. 2.

Fig. 7 is a section through the firing device.

Figs. 8 and 9 are details in elevation of 45 another form of charging device for the magazine.

The body portion of the shell includes an outer casing designated 10 having connection at 12 with a nose portion 14, and having 50 connection at 15 with a breech portion or base portion 16. A shaft 18 extends longitudinally of the shell and coincident with the main axis thereof, the forward end of the shaft being mounted within the nose 55 portion and the rear end thereof being mounted in the base portion.

The structure including the casing 10, the shaft, the nose portion and base portion constitutes the rotary unit, this unit also including an inner sleeve 20 which surrounds 60 shaft 18 and which has a limited longitudinal movement on the shaft, the sleeve being normally retained in proper position by means of a spring 21 encircling the shaft and adapted to exert tension on the sleeve 65 for spacing the latter and the magazine from the nose portion mounted as specified below. This spacing function serves to retain the magazine in such position that the firing device carried by the magazine is normally out of contact with the nose portion and therefore in inoperative position (the firing pin *per se* being mounted as shown in Fig. 7). The sleeve 20 is provided with a longitudinal slot 22 engaged by a pin or the 70 like 23 carried by the shaft and preventing the rotary movement of the sleeve with reference to the shaft.

The magazine 25 is provided with end portions 26 and 27 having centrally located 75 apertures therein within which is mounted a sleeve 28 forming a rigid element of the magazine and permitting the entire magazine to rotate with reference to the inner sleeve 20. While reference is made to the 80 rotation of the magazine with reference to the shaft and the inner sleeve, for convenience, it is of course understood that the body portion proper rotates independently of the magazine during flight.

Ball bearings are provided to permit of the rotation of the body portion with the minimum degree of friction, the race members for these bearings being designated 85 respectively 31 and 32, the members 31 being carried rigidly by the inner sleeve 20 and the members 32 by the end portions of the magazine. The series of balls within the bearings is shown at 34 at each end of the magazine.

End portion 26 of the magazine is provided with a firing device including a resiliently mounted firing pin 35 operating within a tubular member 36 secured in position by a lock nut 37. A tubular flanged member 38 surrounds one end of the tubular member first named and serves as a spacing device between the adjacent end portion of the magazine and the nose portion of the shell. The tubular member 36 is provided with laterally extending openings or 105 ports communicating with the main bore of 110

said tubular member, and a screw 39 retains the percussion cap in position to receive the impact of the firing pin.

The breech portion 16 is provided with a bore 45 terminating at the outer end of said breech portion in an enlarged bore or recess 46 adapted to be closed by a screw plug 47. A tubular member 48 is mounted within the bore, is movable longitudinally therein and constitutes a filling tube. The enlarged end 50 extends within a recess 51 of the screw plug, and the opposite end of the filling tube is adapted to telescope with reference to a tube 53 extending through end member 27 of the magazine. The filling tube and the tube 53 are in engagement only during the filling operation, being normally held out of engagement by a spring 55. After filling the magazine, the tube 53 is closed by introducing any suitable material in plastic condition through the filling tube.

When the projectile is rotated upon engagement with the rifling of the gun, the body portion, including casing 10 the nose portion and base, the shaft and the inner sleeve, are rotated independently of the magazine, the latter acting in a measure as a balanced and stationary object having sufficient inertia to resist rotation, such as would ordinarily be imparted by the rotation of the body portion.

In Figs. 8 and 9 I have shown a form of filling device comprising a tubular member 48, having a flange 50 and having its opposite end tapered in order that it may fit between the members 60 and 61 pivoted at 62 and normally retained in closed position by means of a U-shaped spring 63 mounted at 64.

The tapered portion of the filling tube is forced between pivoted members 60, 61, and the tube may then enter the filling aperture 53. This aperture is closed upon the withdrawal of the tube and when elements 60, 61 assume their normal position, illustrated in Fig. 8.

What is claimed is:

1. In a projectile, a casing including a body portion, a nose portion and base, a magazine mounted in the casing, means for supporting the casing for permitting the latter to have a movement independent of the magazine, a firing device connected with said magazine and operated by impact with the nose of the projectile, and means for charging the magazine, comprising a longitudinally movable tube mounted in the base.

2. In a projectile, a casing including a body portion, a nose portion and a breech portion, a shaft extending through the body

portion and having its ends mounted within the nose portion and breech portion respectively, a magazine surrounding said shaft, the shaft rotatable independently of the magazine, and a firing device operated by the movement of the magazine longitudinally on the shaft.

3. In a projectile, a casing including a body portion, a nose portion and a breech portion, a shaft extending through the casing and mounted within the nose portion and breech portion, a sleeve carried by the shaft, and a magazine through which said sleeve and shaft extend longitudinally, said sleeve and shaft being rotatable with reference to the magazine and the sleeve and magazine being slidable longitudinally on the shaft, and means operable upon such longitudinal movement for firing a charge.

4. In a projectile, a casing, a shaft extending longitudinally thereof, a sleeve having a limited movement longitudinally of the shaft and non-rotatable with reference thereto, resilient means carried by the shaft and controlling the longitudinal movement of the sleeve, and a magazine inclosing said shaft and sleeve, the shaft and sleeve being rotatable with reference to the magazine.

5. In a projectile, a casing, a shaft extending axially thereof, a sleeve surrounding said shaft and non-rotatable with reference thereto, an outer sleeve surrounding the sleeve first named, a cylinder for containing a charge, end walls for the cylinder serving to rigidly mount the outer sleeve, permitting the casing, shaft and inner sleeve to rotate with reference to the outer sleeve and cylinder.

6. In a projectile, a magazine, a body portion rotatable independently of the magazine, and a firing device operated by the longitudinal movement of the magazine within the body portion.

7. In a projectile, a magazine, an outer casing, a nose portion, means permitting the rotary and longitudinal movement of the casing and nose portion with reference to the magazine, and means whereby the charge may be fired as the result of said longitudinal movement.

8. In a projectile, a casing including a base, a magazine within the casing, and with reference to which the casing is rotatable, the magazine being movable longitudinally in the casing, and a tube for filling the magazine and movable longitudinally through the base.

In testimony whereof I affix my signature.

CLARENCE JANES.
